UNITED STATES PATENT OFFICE.

EMILE DEWOITINE, OF TOULOUSE, FRANCE.

AEROPLANE CONSTRUCTION.

Application filed July 8, 1924. Serial No. 724,856.

To all whom it may concern:

Be it known that I, EMILE DEWOITINE, a citizen of France, and a resident of Toulouse, Haute-Garonne Department, France, have invented certain new and useful Improvements in Aeroplane Constructions; and I do hereby declare the following to be a full, clear, and exact description of the invention such as will enable others skilled in the art 10 to which it appertains to make and use the same, reference being had to the accompanying drawings, and to letters or figures of reference marked thereon, which form a part of this specification.

15 My invention relates to improvements in aeroplane construction.

In the first place, it concerns the mounting of an engine in the overhung position at the side of the main body of an aeroplane 20 by means of discs, tubes and cables in such manner that the frame composed of the said elements shall be entirely rigid, this result being obtained without depending upon the flexion of any one of the elements.

25 Secondly, the invention has for its object the construction of an all-metal hull, wherein the internal portion and the walls are entirely free from any trellis structure, and whose bending strength is due to the 30 approved connection between an internal framework consisting of transverse members and spars, and the sheet metal covering elements of suitable thickness. The said construction serves chiefly for the main body 35 of the aeroplane containing the passengers and freight, but its use may be extended to all objects which are to be contained within an element having a perfectly continuous and streamlined surface.

40 The invention lastly relates to the construction of a spar whereof the beams and struts have the tubular form and the inclined elements consist of cables or piano wires.

45 The following description, together with the appended drawings which are given by way of example, sets forth my said invention.

50 Figs. 1 and 2 are respectively diagrammatic front elevational and plan views of an aeroplane body provided at each side with an engine frame.

Fig. 3 is a diagrammatic detail view of Fig. 1.

Fig. 4 is a view of the engine frame on a larger scale.

Fig. 5 shows the main body of the aeroplane.

Figs. 6 and 7 are detail views.

Fig. 8 shows one of the spars on a large scale.

The engine frame comprises a sheet metal member *a* to which the engine is secured by the bolts *b*, and which is mounted at the end of four main tubes *c d e f* traversing two circular discs *g* and *h*, each disc consisting of two metal plates connected together by U-shaped members which are riveted to the periphery, as shown in Fig. 4.

The said tubes are cross-braced by the cables *i* and *j* in the four lateral planes determined by their axes in the region between the two discs. Forwardly of the front disc, i. e. between the latter and the said engine plate, the cross-bracing is maintained at the upper and lower faces, the bracing being effected not by cables but by a single tube *k* disposed in each of the two planes of the lateral faces.

The frame composed of the four tubes and the two discs being thus made rigid, the same is to be secured to the aeroplane body; this result is obtained in the following manner, Figs. 1 to 4. Two pairs of tubes *l* and *m*, *n* and *o*, are fitted between the two walls of the discs *g* and *h* and riveted to the sheet metal of these latter; they are provided with the connecting members *p* and *q*, *v* and *s*, respectively, cooperating with like members mounted upon corresponding tubes which are fitted into the discs or transverse elements of the aeroplane body and are in line with the tubes *l* and *m*, *n* and *o*, the said connecting members being bolted together. To obviate all flexion, suitable cross-bracing cables *t* and *u* are disposed on the four lateral faces determined by the axes of the said tubes. The device is mounted and dismounted by means of 4 bolts and 8 . . . stretchers at the minimum; the frame and engine can be removed as a whole and replaced by a like frame comprising an engine ready to operate. But the engine may also be removed if desired without interfering with the frame.

The engine frame is covered with sheet metal plates of suitable shape which are mounted upon the two discs g and h so as to offer a streamline surface. The piping 5 and the control cables are disposed along the connecting tubes and within the streamline facing, being provided with suitable connections or unions adjacent the said connecting members of the tubes. The shape 10 of the engine frame is well adapted for the installation of fuel feeding devices within the parallelepipedon formed by the tubes c d e f and their cross-bracing.

Figs. 5 to 7 show an aeroplane body also 15 comprising transverse members or discs, and upon which may be mounted the engine frames as above described; the said body consists essentially of the transverse discs a^1 , b^1 , etc., of a very light construction, the spars c^1 d^1 , etc., and the longitudinal strips e^1 f^1 etc., the whole being covered by sheet metal plates of streamline shape which are riveted along the said strips and discs. The latter are usually of an oval form, but may 20 be otherwise shaped provided the outlines are well rounded; the discs consist of two thin sheet metal members suitably cut out and forming two parallel cheeks which are joined upon the whole of their inner contour 25 by small U-shaped pieces of thin sheet metal which are bent into shape and form a cross connection; a like construction is employed for all the internal outlines of the cut-out parts of the disc, such as g^1 . As 30 concerns the outer contour h^1 , the covering sheet metal serves as a cross-bracing, and it is mounted by means of small corner pieces i made of the same sheet metal as that of the walls and the said U-pieces, and riveted by 35 one flange to the contour portion of the said cheek while the other flange has secured thereto the sheet metal covering. The said double-walled discs are completed by intermediate transverse members of light construction 40 which consists of a single thickness of sheet metal, provided with a corner piece as above stated. The number and spacing of the said transverse members is variable; the latter are provided with slots of rectangular 45 section cooperating with the spars and strips. 50

These latter members differ only from each other in the thickness of the sheet metal entering into their construction; the said spars are shown as four in number in the drawings, but a greater number can be employed, the number of the intermediate strips is also variable, depending upon the spacing to be allowed between two consecutive strips. Both spars and strips may be 55 given a U cross section, as shown in Fig. 6; they are secured in the said slots of the discs by small corner pieces j^1 , Fig. 7, and comprise the cheeks k^1 , Fig. 6, to which the sheet metal covering is secured.

60 This latter consists of plates which can be

preliminarily given a streamline shape if required—this being generally the case for the parts having a pronounced curvature such as the top and bottom of the hull—and are mounted upon the said discs and strips, being riveted as above stated to the cheeks of the spars and strips and to the flanges of the corner pieces of the discs; obviously, the junction of any two plates will coincide with one of the strips or corner pieces, the edges 70 of the sheets being in the overlapping position. The whole is maintained in place by light copper bolts, the latter being then removed in turn and replaced by rivets which are inserted from the interior of the hull and riveted at the exterior; from what precedes it is supposed that a workman can be stationed within the hull or can introduce his arm with the riveting tool.

80 By this perfect connection, the sheet metal covering will participate in the general strength of the construction, so that the hull will now act as a unit body, and in designing the same one may apply all the formulæ 85 which are based upon the rigidity of straight sections, care being taken however to provide for the possible yielding of the whole 90 of the compressed region.

The invention further relates to the construction of tubular spars for aeroplane 95 wings.

The said spars, Fig. 8, comprise an upper beam a^2 and a lower beam b^2 consisting of the tube sections c^2 d^2 e^2 which are fitted into each other and riveted together, ends of the tubes being turned to a tapered shape in order to facilitate the insertion, the tube d^2 is 100 fitted into the tube c^2 to the required distance (depending upon the number of rivets f^2 to be used) and the rivets f^2 and the tool are inserted through the open end g^2 ; when the riveting has been performed, the tube e^2 can be fitted into the tube d^2 , and so on.

105 The vertical struts h^2 are mounted in place after the completion of the tubular beams, and they are secured thereto by small corner pieces having a slight curvature z^2 which are riveted to the struts and screwed to the said beams. The trellis structure is mounted in the last place, cables or piano wires being stretched between forked connectors j^2 which are secured to the said beams by the bolts k^2 .

110 Obviously, the hereinbefore described arrangements are susceptible of various modifications without departing from the spirit of the invention.

What I claim is:

1. An engine frame for aeroplanes which 115 is mounted in the overhang position at the side of the main body and consists of discs, tubes, and cables connecting the said discs, forming a rigid structure to which is secured the plate supporting the engine, and 120

tubes connecting the said structure with the aeroplane body.

2. An engine frame for aeroplanes which is mounted in overhanging position at the 5 side of the aeroplane body, comprising discs, tubes and cables connecting said discs to form a rigid structure to which the engine supporting plate is to be secured, tubes for

connecting said structure to the aeroplane body, transverse discs, longérons connected 10 to the discs at their circumference and sheet metal covering said longérons.

In testimony that I claim the foregoing as my invention, I have signed my name hereto.

EMILE DEWOITINE.
